UNITED STATES PATENT OFFICE.

JOHN JUROKA, OF CLEVELAND, OHIO.

RAILWAY-TRACK CONSTRUCTION.

1,377,489.

Specification of Letters Patent. Patented May 10, 1921.

Application filed October 6, 1920. Serial No. 414,973.

To all whom it may concern:

Be it known that I, JOHN JUROKA, a citizen of the United States of America, residing at Cleveland, in the county of Cuyahoga and State of Ohio, have invented certain new and useful Improvements in Railway-Track Construction, of which the following is a specification.

This invention relates to certain new and useful improvements in railway track construction and has for one of its particular objects the provision of improved tie construction whereby the several ties of a railroad are properly spaced as well as efficiently held against relative lateral displacement, and whereby the rails are efficiently fastened to the ties.

Another object is to provide a much improved tie construction which is of such simple and durable form as well as so light in weight as to meet with all the requirements for a successful commercial use.

Other objects will appear as the nature of the invention is better understood, and the same consists in the novel form, combination and arrangement of parts hereinafter more fully described, shown in the accompanying drawings and claimed.

In the drawings, wherein like reference characters indicate corresponding parts throughout the several views,

Figure 1 is a side elevational view of a portion of a railway track constructed in accordance with the present invention,

Fig. 2 is a view of Fig. 1 partly in top plan and in horizontal section, and partly broken away,

Fig. 3 is a transverse sectional view taken upon line III—III of Fig. 1,

Fig. 4 is a view similar to Fig. 3 taken upon line IV—IV of Fig. 1,

Fig. 5 is a sectional view taken upon line V—V of Fig. 4,

Fig. 6 is a view of one end of one of the ties in blank form before being bent to provide rail base engaging lips, and

Fig. 7 is a fragmentary perspective view of an end portion of one of said ties.

Referring more in detail to the several views, the present invention contemplates the provision of a railway track construction embodying metallic ties 5 all in the

general form of I-beams and each having the end portions of its web stamped and bent outwardly to provide spacing tongues 6 which extend at right angles to the ties as shown more clearly in Figs. 1 and 2 so as to insure quick and ready placement of the ties the proper distance apart. The ends of the upper flanges of each tie are provided with pairs of extensions or legs 7 which are bent upwardly and inwardly so as to provide lips for reception of the base flanges of the rails 8 at the outer sides of the latter as shown in Fig. 3. Between the joints of the rail sections 8 the opposite or inner base flanges of said rail sections are engaged by clamping plates 9 of the usual form which are secured upon the upper flanges of the ties by bolts and nuts generally indicated by the numeral 10 and shown as passing through said plates as well as through the upper flanges of the tie. In order to provide a more durable fastening at the rail joints and to facilitate repair of said joints, a single member 11 is utilized upon the upper flanges of the ties instead of two clamping plates 9, said member 11 being of integral formation, bolted as at 12 centrally to the tie and formed at its ends to conform with the shape of said 10 clamping plates 9.

It will be seen that when the ties 5 with their spacing tongues 6 are embedded in "ballast," said ties will be effectively anchored against movement, particularly in a lateral direction by the tongues 6.

From the foregoing description it will be seen that I have provided an extremely simple railway construction involving efficient tie anchoring and rail fastening devices 90 wherein the tie construction is quite light in weight so as to meet with the particular requirements for a successful commercial use.

Minor changes may be made without departing from the spirit and scope of the invention as claimed.

What is claimed as new is:—

1. In railway construction, a metallic tie of I-beam formation having tie spacing tongues struck from the web thereof and extending at right angles to the same, and means upon the upper flanges of said tie for securing rails thereon.
2. In railway track construction, a metal-

lic tie of I-beam formation having tie spacing tongues at the opposite ends thereof struck from the web of the same.

3. In railway track construction, a metallic tie of I-beam formation having tie spacing tongues at the opposite ends thereof struck from the web of the same, and means

for clamping rails upon the upper flanges of said tie including extensions upon the ends of said upper flanges bent upwardly and inwardly to form rail base flange engaging lips. ¹⁰

In testimony whereof I affix my signature.

JOHN JUROKA.
